UNITED STATES PATENT OFFICE.

ROBERT B. WEAVER, OF DETROIT, MICHIGAN.

GEAR-GRINDING DEVICE.

1,017,612.

Specification of Letters Patent.

Patented Feb. 13, 1912.

Application filed April 12, 1911. Serial No. 620,568.

To all whom it may concern:

Be it known that I, ROBERT B. WEAVER, a citizen of the United States, and a resident of the city of Detroit, in the county of Wayne and State of Michigan, have invented a new and useful Improvement in Gear-Grinding Devices, of which the following is a specification.

This invention relates to devices for grinding bevel and other toothed gears, and it has for its principal objects to produce a grinding machine by the use of which the high spots on the teeth and rubbing surfaces of intermeshing gears may be effectually removed without affecting the low spots, whereby the rubbing or working faces are accurately shaped, and to attain certain advantages hereinafter more fully appearing.

There have been numerous devices arranged for grinding bevel and other gears where the large gear being ground is driven directly by the pinion or companion gear also being ground, the rubbing faces of both of which are ground with emery or other abrasive material sprinkled thereon. This, however, has not been a success, because if there is any irregularity in the spacing of the teeth, although infinitesimal, it is maintained until the grinding is finished. In fact, it will at times grow worse. This invention, therefore, consists essentially in a gear grinding machine having a pair of accurately cut driving or master gears which are meshed together snugly with no back lash, said master gears carrying the devices adapted to receive the intermeshing gears to be ground. The invention further consists in the parts and in the arrangements and combinations of parts hereinafter described and claimed.

In the accompanying drawing which forms part of this specification and wherein like symbols refer to like parts wherever they occur, the figure represents, partly in vertical section and partly in elevation, a machine adapted for grinding bevel gears in accordance with my invention.

As illustrated in the drawing, the machine comprises a yoke or frame 1 having two bearing portions 2 and 3, respectively, arranged at right angles to each other. Journaled in the bearing portion 2 is a spindle 4 having on its inner end a bevel gear 5. The outer end portion of the spindle 4 is screw-threaded, as at 6, to receive an internally screw-threaded ring or collar 7,

and the portion adjacent to the gear 5 is also screw-threaded, as at 8, to receive a similar ring or collar 9. The rings 7 and 9 are adapted to bear respectively against the opposite ends of the bearing portion 2; and by adjusting said rings on the spindle 4 the latter is also adjusted lengthwise in its bearing.

The spindle 4 is bored axially to receive a cylindrical shank portion or stud 10 of a gear-holder which is splined or feather-keyed to rotate fixedly therewith, but permitted independent endwise movement. The shank is provided on its inner end with a face-plate or disk 11 having pins 12 adapted to fit perforations in an annular portion 13 of a bevel gear 14 to be ground, as herein-after set forth. The outer end portion 15 of the shank 10 is reduced considerably in diameter and is rotatably fitted in a bearing sleeve 16, while the extreme end portion 17 is further reduced and screw-threaded to receive a retaining nut or thrust collar 18.

The bearing sleeve 16 is externally screw-threaded and secured in a screw-threaded bore in the split lower portion of a bracket extension 19 on the yoke or frame 1; and a clamping bolt 20 is obviously provided on the split portion of the bracket extension 19 whereby the bearing sleeve may be securely held in position. By adjusting the bearing sleeve in and out on the bracket extension 19, obviously the shank 10 carrying the face-plate or disk 11 is also adjusted with respect to the spindle 4.

Journaled in the bearing 3 is a spindle 21 having on its inner end a bevel pinion 22 adapted to mesh with the master gear 5. It is to be here noted that the gear 5 and pinion 22 are accurately and correctly cut so as to fit snugly with no back lash. The spindle 21 is screw-threaded, as at 23 and 24 to receive thrust collars 25 and 26, respectively, similar to the collars 7 and 9 which are provided on the above mentioned spindle 4. By adjusting the respective collars on the spindles 4 and 21, said spindles may be adjusted so that the gear 5 and pinion 22 are brought together into proper mesh. The several thrust collars may be held in place by set screws 27 or other suitable securing devices.

The spindle 21 is bored axially to receive a shank or stud 28 which is splined to rotate fixedly therewith, but permitted endwise adjustment in a manner similar to

- the before mentioned shank 10. The inner end portion 29 projects beyond the pinion 22 and is tapered to receive a counterpart axial taper bore or seat in a bevel pinion 30 to be ground in connection with the gear 14. The extreme end portion 31 of the shank or stud 28 is reduced and screw-threaded to receive a securing nut 32 adapted to clamp the pinion 30 on the taper 29.
- 10 The outer end portion 33 of the shank or stud 28 is reduced in diameter and journaled in a bearing sleeve 34 adjustably mounted in a bracket extension 35 of the frame 1 in a manner similar to the before mentioned bearing sleeve 16. The extreme outer end portion 36 of the shank is further reduced and screw-threaded to receive a retaining nut or thrust collar 37.
- The master gears may be driven by any 20 suitable means, but a pulley 38 is preferably keyed onto the upper end portion of the spindle 21 which carries the pinion 22; and this pulley is driven by a belt 39. The abrasive material may be dusted or 25 sprinkled onto the gear teeth by hand or from a suitable chute; but it is preferable to place a casing 40 about the gears to be ground to retain the grinding material in contact with said gears.
- 30 In the operation of the machine, the gears to be ground are placed on the respective holders therefor, and the spindles for the master gear 5 and pinion 22 are adjusted in their bearings so that said gear and 35 pinion mesh with exact nicety and without back lash. The respective bearing sleeves 16 and 34 are next adjusted in the bracket extensions 19 and 35 so that the carriers for the gears to be ground are adjusted 40 with respect to the spindles of the master gears to bring said gears to be ground just so closely together that, when they are revolved, they touch on a few of the high spots of their rubbing faces. Then the 45 abrasive material is applied to the gears or filled into the casing 40, as the case may be, and the gears are rotated together. The master gears being accurately cut and set in mesh without any back lash, the gears 50 which are to be ground are compelled to revolve at their correct velocity ratio, irrespective of any high spots or low spots, and the abrasive material acts upon the touching high spots without affecting the 55 low spots. After the gears are run in this position for a short time, they are adjusted closer together until they touch at other high spots, and so on. As the high spots are 60 gradually worn down, the gears are fed closer together until a uniform bearing is had all over the surfaces of the teeth. Obviously, therefore, this uniform bearing will then represent an absolutely uniform and correct velocity ratio between the two 65 gears which have thus been ground. By this

method of grinding, bevel and other gears are produced which are extremely accurate and quiet running.

While the machine illustrated in the drawing is particularly adapted for bevel gears, it is obvious that the invention is applicable to any form of intermeshing gearing in which one of the gear members is toothed, such as spur gears, spiral gears, and worm gearing. Therefore, I do not 75 wish to be limited to the constructions and arrangements shown.

What I claim is:

1. A machine for grinding toothed gears, comprising means for holding intermeshing gears to be ground in correct working position, and a positive driving device independent of said intermeshing gears for revolving them at their correct velocity ratio. 80

2. A machine for grinding toothed gears, comprising means for holding intermeshing gears to be ground in correct working position, means, external of themselves, for revolving said gears at their correct velocity ratio, and means for maintaining abrasive 90 material in contact with the coöperating rubbing faces of said gears.

3. A machine for grinding toothed gears, comprising rotatory means for holding intermeshing gears to be ground in exact working position without back lash, means, independent of the gears to be ground, for rotating said rotatory gear-holding means to positively drive said gears to be ground at their correct velocity ratio, and means for 95 maintaining abrasive material in contact with the coöperating rubbing faces of said gears. 100

4. A machine for grinding toothed gears, comprising accurately formed intermeshing driving gears without back lash, means for mounting intermeshing gears to be ground in fixed relation to the respective driving gears so as to be rotated positively therewith, and means for adjusting the gears being ground into closer mesh. 105

5. A machine for grinding toothed gears, comprising rotatory carriers for intermeshing gears to be ground, and means for positively driving said gear-carriers, comprising accurately fitting intermeshing gears without back lash, whereby said gears to be 115 ground are positively driven at their correct velocity ratio by means external of themselves.

6. A machine for grinding toothed bevel gears, comprising a coöperating pair of rotatory carriers adapted to hold an intermeshing pair of gears to be ground in correct working position, a pair of accurately cut beveled master gears fixed respectively on said rotatory gear-carriers and set in mesh free of back lash, and means for adjusting said rotatory gear-carriers with respect to each other so as to bring the gears to be 125 130

ground into correct working position and whereby said gears are driven at their correct velocity ratio.

7. A machine for grinding toothed bevel gears, comprising a pair of spindles having fixed thereon a pair of snugly fitting accurately cut bevel gears without back lash constituting positive driving means therefor, and a pair of gear-carriers mounted axially 10 on said spindles and respectively fixed to rotate therewith, but being adjustable lengthwise thereof, said gear-carriers being adapted to receive a pair of intermeshing bevel gears to be ground.
- 15 8. A machine for grinding toothed bevel gears, comprising a pair of spindles having fixed thereon a pair of snugly fitting accu-

rately cut bevel gears constituting positive driving means therefor, a pair of gear-carriers mounted axially on said spindles and 20 respectively fixed to rotate therewith, but being adjustable lengthwise thereof, said gear-carriers being adapted to receive a pair of intermeshing bevel gears to be ground, and means for maintaining an abrasive material in contact with the cooperating rubbing faces of said bevel gears being ground.

Signed at Detroit, Michigan, this 7th day of April, 1911.

ROBERT B. WEAVER.
